UNITED STATES PATENT OFFICE

JOSEPH SCHWEISS, OF ST. LOUIS, MISSOURI, ASSIGNOR TO CARTER CARBURETOR CORPORATION, OF ST. LOUIS, MISSOURI, A CORPORATION OF DELAWARE

CARBURETOR

Application filed July 6, 1929. Serial No. 376,878.

This invention relates to carburetors and more particularly to suction operated spray carburetors of the type in which the fuel is lifted or sucked into the mixing chamber by the suction of the engine. In carburetors of that type, it is usual to provide some means for restricting the admission of air to the mixing chamber when it is desired to start the engine; otherwise the comparatively low suction developed by the engine when it is rotated at a low speed by the starting device would be insufficient to draw a proper quantity of fuel into the mixing chamber.

It often happens that when carburetors of this type are adjusted for starting, that is to say, when the air inlet to the mixing chamber is restricted, the engine will start, but fail to run. This is due to the fact that the operator is unable to open the choke or other restriction to the air inlet quick enough after the engine starts to fire, with the result that an over-rich mixture is drawn into the engine by the comparatively high suction which is produced as soon as the engine starts to run under its own power.

It will be understood that the electric or other starting devices which are used for starting internal combustion engines are capable of turning the engine over only at a comparatively low speed, say, thirty to fifty revolutions per minute. On the other hand, the lowest speed at which many engines will run under their own power may be two or three hundred revolutions per minute. It will be obvious that the air inlet must be much more highly restricted in order to produce an appreciable suction at the low speed delivered by the starter, than would be suitable for operation at the comparatively high speed at which the engine runs under its own power.

The general type of carburetors to which this invention relates includes two classes known as "plain tube" and "air valve" carburetors. The invention in its broader aspects is applicable to both of these types of carburetors, but I have shown it in connection with a plain tube carburetor, and certain more specific features of the invention are especially adapted for use with plain tube carburetors. It will be understood by those skilled

in the art that the term "air valve carburetor" implies a suction operated spray carburetor having one or more air passages which are normally closed by a suction operated valve, this valve usually controlling the so-called auxiliary air passage which does not usually enclose the main jet of the carburetor. The term "plain tube carburetor" will be understood to imply one in which no suction operated valve is employed under normal operating conditions, although such a valve may be used, as in the case of the present invention, for operation under abnormal conditions such as starting.

As is well-known to those skilled in the art, the air valve type of carburetor is highly desirable for starting purposes on account of the comparatively low starting speed and the great variation in suction from cranking speed to the speed at which the engine is operated for warming up purposes. The suction operated air valve, whether controlled by gravity or spring, is capable of nicely adjusting the air inlet to give a suitable mixture. On the other hand, the air valve carburetor is not desirable for high speed running purposes, as the drag of the air valve on the air stream flowing into the carburetor reduces the amount of air which the carburetor will flow at maximum speed, a difficulty which is not present in plain tube carburetors.

It is an object of this invention to produce a carburetor having automatic means for at least partially relieving the restriction at the entrance to the mixing chamber as soon as the engine begins to run under its own power.

Another and further object of this invention is to produce a simple and easily manufactured carburetor having means for suitably restricting the air inlet for starting purposes and for automatically regulating the restriction after the engine has started. Other objects of the invention will appear from the following specification and the accompanying drawing, referring to which:

Figure 1 is a view partially in section of a carburetor constructed according to my invention.

Figure 2 is a view similar to Figure 1, ex-

cept that the parts are in a different operating position.

The reference numeral 1 indicates a casting forming the main body member of the carburetor. This casting forms the walls of an air chamber 2 to which air is admitted through an air horn 3. A flange 4 of conventional formation is provided for attaching the carburetor to the intake manifold 10 of an internal combustion engine. The flanged member has a passageway there-through comprising a cylindrical portion 5 into which is fitted a Venturi-shaped restricting member 6 which is held in position 15 by a pin 7 or other suitable means. The body member has an annular surface 8 which is provided with a suitable gasket to receive the upper edge of the cup-shaped fuel bowl 9. The body member also has a downwardly 20 extending portion 10 to which the bowl is attached by a nut 11, as shown. The fuel is supplied to the bowl by conventional means (not shown) and maintained at a constant level therein by the usual float 12. The upper 25 part of the extension 10 is provided with a downwardly extending recess 13 which is screw threaded at 14 to receive a standpipe or primary mixing chamber 15. A main jet member 16 of conventional construction supplies fuel from the bowl to the standpipe. The jet 16 terminates at or near a restricted portion or venturi 17 in the standpipe. This venturi or restricted portion is between the main air inlet port 18 for the standpipe and 30 the discharge outlet 19 which is at or near the throat of the Venturi member 6. The standpipe is provided with one or more auxiliary air ports 20 which normally permit the entrance of a quantity of air in addition 35 to that entering through the main air inlet 18. The usual idling tube 21 is provided, and this communicates at its lower end with the fuel bowl and at its upper end with a bore 22 in the body member of the carburetor. 40 This bore discharges at the idling port 23 and is regulated in a conventional manner by the regulating screw 24. An air bleed duct 25 is provided for the idling tube and also a second air inlet port 26. The port 26 45 opens at or near the throat of the Venturi, as shown. A conventional butterfly throttle 27 is mounted on a shaft 28. This throttle is mounted in the passageway 5 at the outlet of the main mixing chamber 29. The standpipe 15 is of considerably smaller diameter 50 at its upper end than the throat of the venturi 6, and the annular space around the body of the standpipe forms a secondary air inlet 30 in addition to the primary air inlet 18, the auxiliary air ports 20, and the bleed 31 which leads to the accelerating well 32. For starting purposes, it is desirable to close the 55 secondary air passage 30, and for this purpose I provide a choke 33 having an operating collar 34 which is operated by the yoke

35. The yoke is mounted on the choke operating shaft 36. The choke is provided with an outwardly and downwardly extending portion to close against the end of the venturi 6, as indicated in Figure 2. A plurality of ports 37 are formed in the choke, and these are normally closed by a valve 38 which is slidably mounted on the choke substantially as shown and retained in position by a ring and groove construction 39, as indicated. The valve member 38 is freely slideable up and down on the choke, but not removable therefrom in ordinary operation.

The operation of the device is as follows:

The carburetor being attached by means of the flange 4 to the intake manifold of the internal combustion engine, the shaft 36 is operated to move the cone 33 into the position shown in Figure 2. This closes the annular passageway between the throat of the venturi and the top of the standpipe and also closes the ports 20.

When the engine is rotated by the starting means, air is drawn into the primary mixing chamber through the ports 18 and 31. This air passing up through the venturi 17 and co-acting with the suction from the engine draws fuel from the jet 16 and mixes with it in the primary mixing chamber or standpipe 15. The mixture thus formed is drawn up into the intake manifold past the throttle valve 27 which is moved to the position shown in Figure 2 for starting. This is for the purpose of permitting the comparatively low suction developed by the engine at starting to act on the jet 16 to withdraw fuel therefrom.

The suction developed by the engine is sufficiently relieved by air entering the ports 18 and 31 so that the weight of the valve member 38 is sufficient to keep the ports 37 in closed position as long as the engine is turning over at a comparatively low speed, but as soon as the engine begins to run under its own power, it runs faster and the increased suction immediately lifts the valve 38 to a position shown by the dotted lines in Figure 2, permitting additional air to enter through the ports 37 and thus forming a suitable mixture for warming up purposes. After the engine is suitably warmed up, the shaft 36 is rotated to the position shown in Figure 1, thus fully opening the annular passageway 30 between the throat of the main venturi and the upper part of the standpipe 15 after which the throttle 27 may be adjusted at will and the engine operated in the usual manner.

I claim:

1. In a carburetor, a main venturi, a standpipe forming a primary mixing chamber and discharging at the throat of said main venturi, said standpipe being smaller than the throat of said venturi and concentric therewith, an air inlet for said standpipe, an annular valve slidably mounted on said stand-

pipe adapted to close against the end of said venturi, a by-pass formed in said annular valve, and a suction operated valve for temporarily controlling said by-pass.

- 5 2. In a plain tube carburetor, a primary air passage constantly in communication with the atmosphere, a secondary air passage normally in communication with the atmosphere, manually operated means comprising an annular valve surrounding said primary air passage for temporarily closing the secondary air passage for starting purposes, a by-pass for said closing means, and suction operated means controlling said by-pass.
- 10 10. In a carburetor of the plain tube type, a main venturi, a standpipe discharging substantially at the throat of said venturi, said venturi being of larger diameter than the standpipe so as to leave an annular passageway therearound, an annular valve slidably mounted on the standpipe for closing said passageway, a by-pass through said annular valve, and means operated by gravity for controlling said by-pass.
- 15 15. In a carburetor of the plain tube type, a main venturi, a standpipe concentric with said venturi, said venturi being of larger diameter than said standpipe so as to leave an annular passageway normally open through
- 20 20. the venturi, an annular valve slidable on said standpipe and movable into said annular passageway to obstruct the same, a by-pass through said valve, and a displaceable closure for said by-pass.
- 25 25. 4. In a carburetor, a vertically disposed main venturi, a standpipe concentric with said venturi, said venturi being of larger diameter than said standpipe so as to leave an annular passageway normally open through
- 30 30. the venturi, an annular valve slidable on said standpipe and movable into said annular passageway to obstruct the same, a by-pass through said valve, and a displaceable closure for said by-pass.
- 35 35. 5. In a carburetor, a vertically disposed main venturi, a standpipe concentric with said venturi, said venturi being of larger diameter than said standpipe so as to leave an annular passageway normally open through
- 40 40. the venturi, an annular valve slidable on said standpipe and movable into said annular passageway to obstruct the same, a by-pass through said valve, a displaceable closure for said by-pass, said closure being normally held in position to close said by-pass by its own weight and being movable by suction to open said passageway.
- 45 45. In testimony whereof, I affix my signature this 26th day of June, 1929.

50

JOSEPH SCHWEISS.
